UNITED STATES PATENT OFFICE

ALVAH M. GRIFFIN, OF LOS ANGELES, CALIFORNIA, ASSIGNOR, BY MESNE ASSIGNMENTS, TO CONSOLIDATED STEEL CORPORATION, OF LOS ANGELES, CALIFORNIA, A CORPORATION OF CALIFORNIA

FLOATING DECK AND LADDER THEREFOR

Application filed October 18, 1926. Serial No. 142,478.

This invention relates to a floating deck such as employed upon oil tanks, and refers particularly to a floating deck provided with a novel form of ladder.

5 An object of the present invention is to provide a ladder for a floating deck which irrespective of the vertical position of the floating deck, will be always in proper position for ascent to the deck.

10 Various further objects and advantages of the present invention will appear from a description of a preferred form of floating deck and ladder embodying the present invention. For this purpose, reference is made to the accompanying drawings, in which:

Figure 1 is an elevation, partially in vertical section, of the deck and ladder mounted in an oil tank.

Figure 2 is an enlarged elevation at right angles to Figure 1 of the ladder construction.

Figure 3 is a further enlarged elevation of a part of the ladder construction, and

Figure 4 is a section through one of the rungs of the ladder.

25 Figures 5 to 7 inclusive refer to certain modifications of the invention, in which:

Figure 5 is a figure similar to Figure 4 of a slightly modified form of ladder.

Figure 6 is an elevation mainly in vertical section of a modified form of bushing and seal for passing the supporting bars or standards through the deck, and,

Figure 7 represents a plan view of the modified form of ladder.

35 Referring to the drawings, 2 indicates the tank provided with a floating deck 3, which deck may be of any preferred construction, the deck usually being provided with sealing plates 4 extending from the outer periphery of the deck into engagement with the side walls of the tank 2.

In order to provide a means of descent and ascent to and from the deck 3, I provide the deck 3 with a pair of spaced openings 5 in which are placed bushings 6 through which the pair of spaced vertical guide bars or standards 7 are adapted to pass. The lower end of the guide bars or standards 7 are fixed by suitable means 8 to the bottom of the tank 2 while the upper ends 50 of said bar 7 are attached by brackets, con-

sisting of bars 9 and 10, to the upper side walls of the tank.

From the upper ends of the bars or standards 7 is suspended a chain ladder 11 comprising two parallel side chains 12 and 13 which support, at spaced intervals, rungs 14. The rungs 14 are preferably hollow and through the rungs extend bars 18, the outer ends of which extend beyond the chains 12 and 13, and are there provided with rings or hooks or other equivalent means for engaging the guide bars or standards 7 and thus slidably holding the rungs 14 on said bars or standards 7.

The rod 18 preferably is fixed to the side chains 12 and 13 by extending through one of the links of said side chains, and in order to prevent said side chains 12 and 13 from becoming entangled, spacers 17 are provided on the rods 18 between the guide bars or standards 7 and the side chains 12 and 13.

By the ladder construction thus described, a ladder is provided from the top of the oil tank down to the floating deck irrespective of the vertical position of the floating deck 3. Moreover, said ladder has its rungs 14 always in vertical alinement. Furthermore, when the deck 3 is in the upper portion of the tank 2, the excess chains and rungs which must be provided so the ladder may 80 reach the deck in the lower position, neatly pile themselves on the upper ends of the bushings 6 where they are readily payed out whenever the deck 3 is again lowered.

Referring to the modifications shown, in certain cases, the spacers 17^a are provided of somewhat larger size than the spacers 17 of the previous form of the invention, and said spacers 17^a may, if desired, be rigidly attached to the rod 18.

Referring to Figures 6 and 7, the construction of the deck 3 where the standards or guide bars 7 extend therethrough is indicated as slightly modified. The opening of the deck is provided with a tube 19 and at the top of said tube, there are provided a plurality of felt washers 20 held between spaced disks 21 and 22. The disks 21 and 22 are in turn held down by springs 24, which springs are fastened to a disk 25 in turn se-

cured in a suitable manner, such as by bolting to a gage ring 26, whereby the gage ring 26 and disk 25 form a case for enclosing the felt washers 20.

5 By the modifications shown in Figures 5 and 6, the standard or guide bar 7 is wiped free from oil as the deck descends and the escape of vapors around the guide bars or standards 7 is also eliminated.

10 While the particular forms of ladder herein described are well adapted for accomplishing the objects of the present invention, it is understood that various modifications in the details of construction may be made without departing from the invention and the invention includes all of the changes, modifications, and substitution of equivalents as come within the scope of the following claims.

I claim:

20 1. The combination with a floating deck, a pair of guide bars, means for anchoring the bars in a fixed, vertically disposed position extending through the deck, a plurality of rungs slidably mounted on the guiding bars, 25 said rungs being positioned above the floating deck and being adapted to contact with the floating deck when the deck is in the upper position thereby to be supported by the deck in a position to readily pay out when 30 the deck lowers, and a plurality of chains adapted to support the rungs in vertical spaced position, said chains being suspended from near the upper end of the guide bars.

2. In means of the class described, the combination with a floating deck, of guide bars extending through the deck, means for anchoring the bars in a fixed, vertically disposed position, and engaging the deck to maintain the same against rotation in the 40 tank in which the deck is positioned, a pair of chains suspended from their upper ends and extending down to the deck, rungs attached to the chains at spaced intervals, the rungs having loops enclosing the guide bars 45 for slidably mounting the rungs thereon, and bushings in the deck through which the guide bars extend, the lower rung being adapted to contact with the bushing of the deck whereby different numbers of rungs will be supported by the deck one above the other, the 50 number supported depending upon the height of the deck.

3. In means of the class described, the combination with a floating deck, of guide bars 55 extending through the deck and serving to hold the deck against rotation, a pair of chains supported from their upper ends and extending down to the deck, rungs attached to the chains at spaced intervals, means slidably mounting the rungs on said guide bars, and wiping means carried by the deck for removing oil from the guide bars during 60 descent of the deck, the lower rung being adapted to contact with the deck and support the other rungs one above the other 65

when the deck is in the upper position.

4. In means of the class described, a floating deck, a pair of guide bars extending through the deck and adapted to hold the deck against rotation, a plurality of rungs 70 slidably mounted on the guide bars; means for anchoring the bars in a fixed, vertically disposed position, a plurality of chains supporting the rungs in vertical spaced relation, and spacers mounted by the rungs between 75 the guide bars and chains, the deck being adapted to contact with the lower rung and support different numbers of rungs, the number supported depending upon the height of the deck.

5. In means of the class described, a floating deck, a pair of vertically extending standards extending through the deck and contacting with the deck to prevent the deck rotating, wiping means carried by the deck and engaging said standards, means for anchoring said standards in fixed vertically disposed position, a plurality of rungs slidably mounted on said standards, and plurality chain means adapted for suspending said rungs in 80 vertical spaced position, the chains being suspended from near the upper ends of the standards, the deck being adapted to contact with the lower rung and support different numbers of the rungs, the number supported depending upon the height of the deck. 95

Signed at Los Angeles, California, this 4 day of October, 1926.

ALVAH M. GRIFFIN.
